CLAIM

The ornamental design for a scanner for nuclear magnetic resonance tomographic apparatus, as shown and described.

DESCRIPTION

FIG. 1 is a front elevation view of a scanner for nuclear magnetic resonance tomographic apparatus, showing our new design.

FIG. 2 is a rear view thereof.

FIG. 3 is a top view thereof.

FIG. 4 is a bottom view thereof.

FIG. 5 is a right side view thereof, with the left side view thereof being an identical symmetrical view thereof; and,

FIG. 6 is a perspective view thereof.
